Design U.S. Appl. No. 29/508,789, filed Nov. 12, 2014, entitled "Video Projector".

Primary Examiner — Wan Laymon(74) *Attorney, Agent, or Firm* — Nixon & Vanderhye, P.C.(57) **CLAIM**

The ornamental design for a video projector, as shown and described.

DESCRIPTION

FIG. 1 is a top, right perspective view of a video projector in accordance with my new design;

FIG. 2 is a front elevation view thereof;

FIG. 3 is a rear elevation view thereof;

FIG. 4 is top plan view thereof;

FIG. 5 is a bottom plan view thereof;

FIG. 6 is a right-side elevation view thereof;

FIG. 7 is a left-side elevation view thereof;

FIG. 8 is a right side cross section taken along the line 8-8 in FIG. 2;

FIG. 9 is a right side cross section taken along the line 9-9 in FIG. 2;

FIG. 10 is a front cross section taken along the line 10-10 in FIG. 4; and,

FIG. 11 is a top, right perspective view showing an extracted handle of the video projector.

The broken line showing in the drawings is included for the purpose of illustrating portions of video projector and forms no part of the claimed design.
